UNITED STATES PATENT OFFICE.

ERNST CURT MÜHLBAUER, OF DRESDEN-LÖBTAU, GERMANY, ASSIGNOR TO UNIVERSAL CIGARETTEN-MASCHINEN-INDUSTRIE SYSTEM OTTO BERGSTRÄSSER AKTIENGESELLSCHAFT, OF DRESDEN-LÖBTAU, GERMANY.

CIGARETTE-MAKING MACHINE.

1,093,564.

Specification of Letters Patent. Patented Apr. 14, 1914.

Application filed November 12, 1913. Serial No. 800,473.

To all whom it may concern:

Be it known that I, ERNST CURT MÜHLBAUER, a citizen of the Kingdom of Saxony, German Empire, residing in Dresden-Löbtau, in the Kingdom of Saxony, in said Empire, have invented certain new and useful Improvements in Cigarette-Making Machines, of which the following is a specification.

In cigarette making machines producing a continuous rod or string of cigarettes whereof the tips are covered, for instance with metal foil, it is imperative that the blade severing the string or rod of tobacco cut exactly through the middle of each such covering. It is, however, impossible to avoid an inaccuracy in the course of the operation owing to small irregularities in the distance between the gold tippings and the printing, which may already be caused by the varying percentage of moisture in the paper. Therefore the cut will not always be exactly in the middle of the tip covering. In order to compensate these irregularities without varying the velocity of the string and without changing the intervals of the successive cuts, it is necessary to produce for a brief space of time a lead or a delay with regard to the cutter. For obtaining this object it has been proposed to arrange a countershaft in the driving mechanism of the cutter slide, the driving member of which countershaft can be displaced with reference to the driven member. By such displacement of one gear wheel to the other an acceleration or a retard in the travel of the slide can be produced, according to the character of such displacement, and thereby the position of the slide can be varied with reference to the string or rod of cigarettes. It is, however, not only necessary to bring the cutter slide into the correct position to the string, but also the cutting motion of the cutter must be temporarily varied, without changing the number of cuts per minute, so that the cut will be made at the proper moment of the stroke of the slide, even after the latter has been displaced. If, now, with the arrangement suggested the regulating countershaft acts solely on the drive of the cutter slide, a special arrangement will have to be provided for regulating the cutting motion. This, however, necessitates a double adjustment, beside the fact that a double gear is required.

According to the present invention the regulating shaft is arranged in such a manner, that it will act both on the travel of the cutter slide and on the cutting motion of the cutter. The result of this is that with the aid of one single gear and by the adjustment of one single gear wheel both the cutter slide and also the device for imparting the cutting operation to the cutter is brought into the proper relation to the cigarette string, in such a manner, that the cutting motion is regulated in a positive manner with the travel of the cutter slide, so that no irregularities can occur between these two parts.

When changing from one length of cigarettes to another—thus when either the velocity of the string or the number of cutting strokes or cuts is varied—a fresh regulation of the position of the cutter slide relatively to the string is especially required. It will then not be sufficient to slightly displace the members of the regulating shaft with respect to each other to bring the cut also with the new length of cigarette exactly into the middle of the tipping cover. Whereas it was hitherto necessary to partly remove the countershaft wheels for this purpose, so as to allow of the necessary displacement being effected, this is avoided with the present invention by the countershaft consisting of a gear wheel as driven member, which can be rolled around the driving wheel. By thus rolling the driven wheel around the driving wheel it is possible to compensate great differences between the position of the slide and that of the string, as a large angle is available for the lead or the delay, whereas with the suggested older arrangements the displacement is only possible within a small angle.

Figure 1 of the accompanying drawings represents a plan view of one embodiment of this invention, showing the rod feeding mechanism and the rod cutting mechanism in connection with a driving mechanism which embodies the preferred form of my regulating means. Figs. 2 and 3 are diagrams representing the cutter in the erroneous positions which in the ordinary machines it is liable to assume on opposite sides of the normal line of severance. Fig. 4 represents on an enlarged scale a vertical longitudinal section of the primary sectional

shaft which serves as a combined driving and regulating shaft for the machine and the differential gear operatively connecting the two sections thereof. Fig. 5 represents on an enlarged scale a plan view of the sectional primary shaft, the differential gears operatively connecting the sections thereof, the sectional secondary shaft, the transmitting gears operatively connecting the parallel sections of said shafts respectively and parts of the transmitting mechanisms for communicating motion from the latter to said rod feeding and rod cutting mechanisms.

The same reference letters indicate corresponding parts in the different figures.

The rod feeding mechanism may be of any suitable construction. As illustrated in the drawings it comprises the endless belt *b* and its immediate driving devices *a*, which need not be here described in detail. The rod cutting mechanism may also be of any suitable construction comprising an ordinary cutter slide *d* carrying a laterally movable cutter *c* for severing the cigarette rod. The driving mechanism for said rod feeder and rod cutter includes a secondary shaft composed of two sections *h* and *h'* disposed in alinement and adapted to rotate independently of each other. The section *h* is operatively connected with the immediate driving devices of the feeder by the bevel gears *g*. The section *h'* is operatively connected with the reciprocating devices of the cutter slide by the bevel gears *i*, said reciprocating devices comprising an eccentric *k* and the usual devices appurtenant thereto. The section *h'* is also operatively connected by a cam disk *l* and an arm *m* with a sleeve *n*, which is fitted to the shaft *o* of the cutter holder *e*, so that the rocking of said arm produces a lateral cutting motion of the cutter *c* in the usual manner.

A primary shaft composed of two sections *r* and *v* disposed in alinement and rotatable independently of each other, constitutes the driving shaft of the machine. A spur gear *p'* loose on the section *r* of the primary shaft meshes with a spur gear *p* fast on the section *h* of the secondary shaft and these gears serve to transmit motion from said section *r* to said section *h*. The hub *q* of the gear *p'* serves as a clutch member. A driving pulley and clutch member *q'* rotatable with and slideable on the section *r* engages said hub *q* to start and stop the machine, being actuated by the shipper lever *q''*. A spur gear *w* fast on the section *v* of the primary shaft meshes with a spur gear *w'* fast on the section *h'* of the secondary shaft, whereby motion is transmitted from section *v* to said section *h'*.

A differential gearing transmits motion from the independent section *r* of the primary shaft to the section *v* thereof. This

differential gearing comprises a large pinion *s* fast on the inner end of the section *r* and a smaller pinion *s'* fast on the inner end of the section *v*. A rotatably adjustable disk *x* preferably in the form of a worm wheel, 70 has a hub which is loose on the inner end of the section *r* adjacent to the pinion *s*. This disk is provided on its outer face with a lateral stud *t*. A sleeve *u* loose on said stud has preferably integral therewith at 75 its inner end a smaller pinion *u* which meshes with the larger pinion *s* of the section *r* and at its outer end also preferably integral therewith a larger pinion *u'* which meshes with the smaller pinion *s'* of the 80 section *v*. These pinions are of such relative diameters as to impart the proper relative motions in regular sequence to the rod feeding mechanism and the rod cutting mechanism through the medium of the sectional secondary shaft and the devices connected therewith as hereinbefore set forth.

By turning the rotary disk *x* more or less through the arc of a circle in one direction or the other, the action of the rod cutting mechanism with relation to the rod feeding mechanism may be accelerated or retarded, and such adjustment will simultaneously effect at one operation the longitudinal movement of the cutter slide and the lateral 95 movement of the cutter.

Any suitable means may be provided for turning the adjusting disk *x* to effect the adjustment thereof. The means shown for this purpose comprise peripheral teeth *a'* on 100 said disk and a worm *y* engaging said teeth and disposed on a shaft *y'* which is provided with a hand wheel *z*. As the worm wheel *y* turns the rotary disk *x*, the differential pinions *u* and *u'* are carried bodily 105 by the stud *t* through an arc of revolution and roll on the pinions *s* and *s'*. If the rotary disk be turned in the same direction in which the section *r* rotates such motion of the disk will be added to the motion of 110 said section and the speed of the section *v* will be increased; on the contrary if the rotary disk *x* be turned in a direction opposite to the rotation of the section *r*, such movement will be subtracted from the 115 transmitting motion of said shaft and the speed of the section *v* will be reduced. Thus the cutter may be adjusted during the operation of the machine to the normal line of severance, such as the middle of the band 120 which forms two end tips.

I claim:

1. In a cigarette machine the combination of a cigarette rod feeding mechanism, a cigarette rod cutting mechanism, a secondary shaft composed of independent rotary sections, transmitting means between one of said sections and said feeding mechanism for operating the latter, means between the other section and said cutting mechanism 130

- for imparting a reciprocatory motion to the cutter slide thereof, means between the same section and said cutting mechanism for imparting a lateral oscillation to the cutter 5 thereof, a primary shaft composed of independent rotary sections disposed in alignment, separate gearings between the respective sections of said primary and secondary shafts, a differential gearing connecting the 10 adjacent sections of said primary shaft, and means for adjusting said differential gearing to simultaneously accelerate or retard the diverse movements of said cutting mechanism during the operation of the machine.
- 15 2. In a cigarette machine the combination of a cigarette rod feeding mechanism, a cigarette rod cutting mechanism, a secondary shaft composed of independent rotary sections, transmitting means between one of 20 said sections and said feeding mechanism for operating the latter, means between the other section and said cutting mechanism for imparting a reciprocatory motion to the cutter slide thereof, means between the same 25 section and said cutting mechanism for imparting a lateral oscillation to the cutter thereof, a primary shaft composed of independent rotary sections disposed in alignment, separate gearings between the respective 30 sections of said primary and secondary shafts, a differential gearing connecting the adjacent sections of said shafts and comprising pinions of different diameters fixed on opposite ends of said sections, a rotary toothed disk provided with a hub loose on one of said sections and carrying a lateral 35 stud and a sleeve loose on said stud and provided with pinions of different diameters engaging said primary shaft pinions, and a worm engaging said toothed disk to accelerate or retard the diverse movements of said 40 cutting mechanism during the operation of the machine.
3. In a cigarette machine the combination of a cigarette rod feeding mechanism, a cigarette rod cutting mechanism, a secondary shaft composed of independent rotary sections, transmitting means between one of 45 said sections and said feeding mechanism for operating the latter, means between the other section and said cutting mechanism for imparting a reciprocatory motion to the cutter slide thereof, means between the same 50 section and said cutting mechanism for imparting a lateral oscillation to the cutter 55 thereof, a primary shaft composed of independent rotary sections disposed in alignment, separate gearings between the respective sections of said primary and secondary shafts, a differential gearing connecting the 60 adjacent sections of said shafts and comprising pinions of different diameters fixed on opposite ends of said sections, a rotary toothed disk provided with a hub loose on one of said sections and carrying a lateral 65 stud and a sleeve loose on said stud and provided with pinions of different diameters engaging said primary shaft pinions, and a worm engaging said toothed disk to accelerate or retard the diverse movements of said 70 cutting mechanism during the operation of the machine.

In testimony that I claim the foregoing as my invention, I have signed my name in presence of two subscribing witnesses.

ERNST CURT MÜHLBAUER.
